Primary Examiner — L. A. Grabenstetter(74) *Attorney, Agent, or Firm* — Lathrop GPM LLP; Wm. Tucker Griffith(57) **CLAIM**

The ornamental design for a smartphone holder for air travel, as shown and described.

DESCRIPTION

1. Smartphone holder

Figure 1.1 is a front perspective view of a smartphone holder for air travel showing our new design;

Figure 1.2 is a first rear perspective view thereof; and Figure 1.3 is a second rear perspective view thereof.

The portions of the smartphone holder for air travel shown with white coloring in the drawings form no part of the claimed design.

1 Claim, 3 Drawing Sheets(56)
